DESIGN FOR A PASTRY CUP

Application filed July 30, 1932. Serial No. 44,491. Term of patent 14 years.

To all whom it may concern:

Be it known that I, URBAN A. KREIDLER, a citizen of the United States, residing at 111 Harrison Street, East Orange, in the county of Essex and State of New Jersey, have invented a new, original, and ornamental Design for a Pastry Cup, of which the following is a specification, reference being had to the accompanying drawing, forming part thereof.

Fig. 1 is a side elevation of a cup ice cream cone with my ornamental design applied thereto, Fig. 2 being a cross-section thereof taken on the line 2—2 of Fig. 1.

My ornamental design for a pastry cup consists of two sets or series of sharp edged ribs which are molded on the outside of the pastry cup and intersect substantially at right angles, one set extending circumferentially of the pastry cup and the other set extending longitudinally thereof.

What I claim is:

The ornamental design for a pastry cup, as shown and described.
